C. J. ERICKSON.
SPRING MOUNTING FOR MAGNET ARMATURES.
APPLICATION FILED DEC. 14, 1905.

1,062,586.

Patented May 27, 1913.

UNITED STATES PATENT OFFICE.

CHARLES J. ERICKSON, OF CHICAGO, ILLINOIS, ASSIGNOR, BY MESNE ASSIGNMENTS,
TO FIRST TRUST AND SAVINGS BANK, TRUSTEE, OF CHICAGO, ILLINOIS.

SPRING-MOUNTING FOR MAGNET-ARMATURES.

1,062,586.

Specification of Letters Patent.

Patented May 27, 1913.

Application filed December 14, 1905. Serial No. 291,680.

To all whom it may concern:

Be it known that I, CHARLES J. ERICKSON, a citizen of the United States of America, and resident of Chicago, Cook county, Illinois, have invented a certain new and useful Improvement in Spring-Mountings for Magnet-Armatures, of which the following is a specification.

Broadly considered, my invention contemplates an improved spring-mounting for magnet-armatures, for any desired purpose.

More specifically considered, my invention contemplates an electric bell or ringer provided with an improved spring-mounting for the armature and striker thereof.

Also, and still more specifically considered, my invention contemplates a harmonic or tuned ringer having its armature and striker mounted upon a torsional spring adjusted for a definite pitch or rate of vibration.

My invention relates to electric bells or ringers in general, but more particularly to electric bells or ringers for use in selective party-line or signaling systems, and especially to electric bells or ringers of that particular type known as harmonic ringers.

Generally stated, the object of my invention is the provision of an improved and highly efficient electric bell or ringer.

Special objects of my invention are the provision of an improved and highly efficient harmonic electric bell or ringer for use in party-line telephone systems, or other selective signaling systems; the provision of an improved construction and arrangement whereby a harmonic ringer of this character may have a striker which is supported upon a spring, or which is so connected with a spring that the oscillation or vibratory motion of the striker tends to subject the spring to a twist or torsional strain; the provision of an improved construction and arrangement whereby the striker of a harmonic bell or ringer may be mounted upon a flat spring which extends at a right angle to the striker, and which has its opposite ends secured or supported in such manner that the striker oscillates or vibrates about an axis which extends longitudinally of the said spring; the provision of an improved construction and arrangement for effecting the adjustment of the armature of a harmonic ringer toward and away from the poles of the electro-magnet; the provision of an improved

construction and arrangement for effecting a ready adjustment of the gongs toward and away from the striker of the harmonic ringer; the provision of an improvised construction and arrangement whereby the spring upon which the striker of the harmonic ringer is mounted may be secured upon and at right angles to the yoke which connects the cores of the electro-magnets; and the provision of certain details and features of improvement tending to increase the general efficiency and serviceability of a harmonic ringer of this particular character.

My present invention is in the nature of an improvement on the bell or ringer disclosed and claimed broadly in application No. 292,187, filed by me in the United States Patent Office on the 18th day of December, 1905.

To the foregoing and other useful ends, my invention consists in matters hereinafter set forth and claimed.

In the accompanying drawings, Figure 1 is a front elevation of a harmonic ringer embodying the principles of my invention, a portion of one of the gongs being broken away to show the manner of mounting the same. Fig. 2 is a vertical section on line 2-2 in Fig. 1. Fig. 3 is a horizontal section on line 3-3 in Fig. 1. Fig. 4 is a detail plan view of one of the adjustable gong-mountings. Fig. 5 is a detail plan view of the spring or reed upon which the striker and armature are mounted. Figs. 6 and 7 are detail views illustrating another way of mounting the torsional spring.

As thus illustrated, my improved harmonic ringer comprises an upper bracket-plate A to which are secured the gongs B. Each gong is mounted upon a swinging mounting C, as shown more clearly in Fig. 4. As illustrated, each gong-mounting is pivoted at its rear end by a screw c, and provided at its forward end with a slot c¹ to which extends a fastening-screw c². With this arrangement, the said gong-mountings are adapted to be swung about their rear pivotal points to bring them nearer together or farther apart, according to requirements. These gong-mountings are preferably raised or arched at their middle portions, so as to support the gongs in suitably elevated positions. The gongs are secured to their respective mountings by thumb-nuts or screws b. A lower bracket-plate D is sus-

pended from the upper bracket-plate A by hangers *a*. It will be seen that the bracket-plate D is secured to the lower ends of these hangers by means of screws *a*¹. The permanent magnet E is secured at its upper end upon the bracket D and retained in place thereon by a strap *d*. As illustrated, the electro-magnets F are also suspended from the bracket-plate D and are secured to the latter by screws *f*. The lower end portion of the magnet-cores *f*¹ are each provided with a circular groove *f*² adapted to be engaged by the inner edges of the frame-like yoke G, as shown in Figs. 1 and 3. This yoke has secured to it a reed or spring H which extends transversely across the under side of the yoke, and which has its end portion secured to the latter by means of the screws *h*. It will be seen that the said reed or spring H is provided at one end with a screw-hole *h*² and at its other end with a screw-notch *h*³ which facilitate the attachment and removal of the spring. The center of the said spring is provided with an opening *h*⁴ adapted to receive the screw-threaded lower end portion of the striker-mounting I; the striker-rod *i*, with its adjustable striker *i*¹, being suitably mounted upon the upper end portion of the said striker-mounting, as shown more clearly in Fig. 2. A nut *i*² clamps the said spring firmly against the shoulder *i*³ on the said striker-mounting. The vibratory armature J has its middle portion provided with an opening through which passes the lower threaded end portion of the striker-mounting I, as shown in Figs. 1 and 2. An adjustable thumb-nut *j* is screwed upon the said striker-mounting and adapted to bear upon the upper surface of the armature J. In addition, a clamping-nut *j*¹ is also screwed upon the said striker-mounting and adapted to bear upon the lower surface of the said armature. In this way, the striker-mounting is rigidly and firmly clamped upon the middle or intermediate portion of the spring or reed H, and the armature is adjustably clamped upon the lower end portion of the rigid upright structure which carries an adjustable striker at its upper end. With the arrangement shown, the lower end portion *e* of the permanent magnet is disposed centrally and at a point just below the middle portion of the armature.

With the foregoing construction, it is evident that the passage, for example, of an alternating current through the coils of the electro-magnets F will cause the armature J to vibrate in the usual and well-known manner. The ringer may be tuned to respond only to a certain frequency, as by tuning the reed or spring H, or by adjusting the striker *i*¹ up or down on its rod *i*. Obviously, however, the bells or ringers can all be of the type or construction shown and described,

and the selectivity of signaling can then be secured by simply adjusting the strikers of the different ringers. Consequently, it is not necessary to construct several different kinds of harmonic ringers for selective party-line telephone systems, as with my improvements the bells or ringers can all be alike, and the difference in their responsiveness to different frequencies can be obtained by simply giving each one a somewhat different adjustment from the others. In other words, the different bells can be made responsive to different frequencies by giving each one practically a different length of striker which, in the theory of harmonic or sympathetic vibration, is technically known as changing the length of the pendulum. Obviously, the strain or tension to which the spring or reed H is subjected is of a torsional character, inasmuch as the armature and striker are rigidly mounted upon the center of the spring in such manner that the oscillation of the armature and striker is about an axis extending longitudinally of the spring. In other words, the spring is held or mounted at its two ends, and the magnets, through the medium of the armature, apply their force or power to the center of the spring, and thus subject the latter to a twisting action.

In assembling the parts, the yoke G is first applied to the lower ends of the electro-magnet-cores and the latter are then secured in place by the screws *f*. If at any time it is desired to remove the said yoke such removal can be accomplished by simply loosening either one or both of the said screws *f*.

With the foregoing construction, it will be seen that my improved harmonic bell or ringer is of the polarized ringer type. Obviously, however, my improvements are applicable to various forms of electric bells or ringers.

If desired, the torsional spring H can be mounted as shown in Figs. 6 and 7. In this case, the yoke G is provided on its under surface with bosses *g* which are of about the diameter of the heads of the screws *h*. With this arrangement, the contact between the spring and the yoke is reduced practically to a minimum and there will be no interference with the desired torsional flexion or action in the spring.

As shown, the striker and armature and torsional spring are all readily removable as a unit from the balance of the structure. In this way, a thicker or thinner spring can be supplied readily and without disturbing the other parts of the structure. For example, the striker *i*¹ has a certain range of adjustment on the striker-rod *i*. However, should this range of adjustment be insufficient to adapt the bell to any desired frequencies of current, the striker and spring and armature can be quickly removed and

another but differently proportioned unit 5 readily substituted therefor. Thus the bell is within limits adapted to be adjusted to any frequency of current, and should this range of adjustment be insufficient another 10 striker and armature and spring can be readily substituted for those already in the bell.

It will be understood, of course, that my 15 improved method of mounting electromagnet armatures can be used in various devices other than electric bells.

It will be seen that my improved spring-mounting for magnet-armatures can be employed in various connections and for various purposes. As illustrated, I have employed it as the armature-mounting for an electric bell or ringer. So far as I am aware a magnet-armature yieldingly held in its 20 normal position by a torsional spring and adapted for a limited and uniform or substantially uniform amplitude of vibration is broadly new. A magnet-armature rigidly secured to and supported by a stiff torsional 25 spring is broadly new so far as I am now aware. Furthermore, a harmonic bell or ringer provided with a stiff torsional spring adjusted for a definite pitch or rate of vibration, so that the bell will only respond to an 30 alternating current of a certain frequency, is broadly new.

It will be seen that the plate A is adapted to be placed on top of the box or casing which incloses the electromagnets and other 35 means for operating the striker. The gongs are on top or outside of the casing, as are also the devices for adjusting the gongs toward and away from each other. In this way it is not necessary to enter the casing 40 for the purpose of adjusting the gongs relatively to each other. This is a great advantage in a ringer, and particularly in a ringer for use in harmonic or selective party-line systems.

45 What I claim as my invention is:—

1. An electric bell comprising gongs, electromagnets, a striker, a flat spring extending at a right angle to the plane in which the striker vibrates, an armature carried by

said spring and rigidly connected with the 50 said striker, and means whereby the striker itself is adjusted toward and away from the armature.

2. In a telephone ringer, electromagnets having their cores extending slightly beyond the end of the coils thereof, a bridge 55 extending across the electromagnets and apertured for the reception of said extended cores, a leaf spring mounted transversely by its ends on said bridge, and an armature 60 and hammer rigidly supported by the spring between the ends thereof for torsional movement therewith in response to the electromagnets.

3. An electric bell or ringer comprising a 65 pair of gongs, a pair of electromagnets, a torsional spring rigidly supported at its opposite ends, and an armature and striker rigidly mounted upon and supported by the middle portion of said spring, the spring 70 being arranged with its length extending at a right-angle to the plane in which the armature and striker oscillate or vibrate.

4. An electric bell comprising gongs, electromagnets, a striker, a torsional spring extending at a right-angle to the plane in which the striker vibrates, an armature carried by said spring and connected with said 75 striker, and means whereby the striker itself is adjusted toward and away from the 80 armature.

5. In a telephone ringer, electromagnets having their cores extending slightly beyond the end of the coils thereof, a bridge 85 extending across the electromagnets apertured for the reception of said extended cores, a torsional spring mounted transversely by its ends on said bridge, and an armature and hammer rigidly supported by the spring between the ends thereof for torsional movement therewith in response to 90 the electromagnets.

Signed by me at Chicago, Cook county, Illinois, this 12th day of December, 1905.

CHARLES J. ERICKSON.
